UNITED STATES PATENT OFFICE.

BERNARD HEIDBRINK, OF AUSTIN, TEXAS.

STEM WINDING AND SETTING WATCH.

SPECIFICATION forming part of Letters Patent No. 433,289, dated July 29, 1890.

Application filed August 14, 1889. Serial No. 320,684. (No model.)

To all whom it may concern:

Be it known that I, BERNARD HEIDBRINK, a citizen of the United States, residing at Austin, in the county of Travis and State of Texas, 5 have invented certain new and useful Improvements in Watches; and I do hereby declare the following to be a full, clear, and exact description of the invention, such as will enable others skilled in the art to which it appertains to make and use the same.

My invention is an improvement in watches; and it has relation particularly to an improvement in mechanism for winding and setting the watch, so that the "movement" may be 15 rendered interchangeable for application to a case, whether arranged for a hunting-case watch or an open-face watch. In watches as commonly constructed a different arrangement is made for the winding and setting 20 mechanism of a hunting-case watch from that of one having an open face. The stem in the former is arranged radially from the figure 3, and that of the latter being placed radially from the figure 12, representing time, respect- 25 ively.

In the drawings illustrating my invention, Figure 1 is an elevation of the face side of a watch-movement with the winding and setting mechanism exposed to view for a crystal 30 face. Fig. 2 is a similar view of a watch with the arrangement applicable to a hunting-case watch. Fig. 3 is an elevation of the back of a watch with the mechanism exposed as applicable to a crystal-face arrangement. Fig. 4 35 is a vertical section taken through the yoke K.

Similar reference-letters indicate like parts in all of the figures.

Referring to the drawings, K is a yoke pivoted at a^2 in a hunting-case arrangement, and 40 at a^3 in the open-face arrangement, having three wings or arms a b c , each provided with axis-points centrally located, respectively.

A is a minute-wheel provided with a pinion a^4 , each having gear-teeth. This wheel 45 and pinion is interchangeable for two positions in the frame of the movement, the one, as in Fig. 2, for a hunting-case arrangement, and the other, as at Fig. 1, for the open-face arrangement upon the pin c^4 .

50 H is the winding-wheel journaled in the cock I, fixed to the movement-frame. On the side of the movement-frame opposite the wind-

ing-wheel H is the cap L, (see Fig. 3,) the teeth of which engage the pinion of the hand-arbor g . Connected with the arbor and pinion f is the wheel h .

x' is the winding-pinion used for the open-face watch, and x is the winding-pinion for the hunting-case arrangement.

d and d' are gear-wheels adapted for use 60 in either of the wings or arms of the yoke K.

l is a crooked lever pivoted at a^6 , provided with a short arm l^2 , adapted to engage a notch in the arm d' of the yoke K. The long arm of the said crooked lever projects outside of 65 the pin of the watch-case, where it terminates with a finger-nail hook in common use.

Pivoted in the frame of the movement of the watch at the outer edge is a lever i , provided with a forked end k' and a pointed end 70 which passes through the winding-pinion x' .

i' is a lever pivoted beneath the lever i , provided with a forked end and a pin m^2 , to be engaged by the said fork k' , one of the prongs of said fork being shorter than the 75 other.

p is a pin projecting inward from the arm a of the yoke K and through a slot m^2 in the movement-frame within reach of the fork of 80 the lever i' .

p^2 is a spindle which connects with the crown M^2 of the stem M through the latter and within reach of the lever i . The lever i is under the influence of a spring k^2 , secured to the movement-frame, and in turn the lever 85 i' is under the influence of the said lever i .

About the axis of the yoke K is arranged a gear-wheel (shown in dotted lines in the drawings) adapted to engage the winding-pinion x x' . An intermediate gear-wheel is 90 arranged to engage the winding-wheel H and the minute-wheel A directly (as in the hunting-case arrangement) and indirectly through gear-wheel d d' , as in the open-face arrangement. The wheel d is pivoted on pin at l^2 in 95 the movement-frame, and a pin c^5 , also in said movement-frame, is intended to form the axis of the wheel A, as in the hunting-case arrangement.

When the yoke K is fixed for the hunting-case arrangement, it being pivoted opposite 100 3 of the dial, the arms or wings a and c are both provided with gear-wheels. The one, d , may now engage the wheel H when the crooked

lever is pushed in, and when the said lever is drawn out the wheel d' will engage the wheel A for setting purposes. It is understood, of course, that the yoke K is rocked about its axis by the engagement of the short arm b' with the notch n in the yoke, so that when the wheel d is engaged by the wheel H the wheel d' is out of mesh with the wheel A, so that the pinion a^4 will not be operative with the setting mechanism.

In the arrangement of the open-face watch the yoke K is pivoted at a point opposite the twelve points of the dial, the arm b of the yoke K carries the wheel d' , and the wheel d is pivoted upon the stud b' . The stud in the arm a for wheel d , as in the hunting-case arrangement, now projects through a slot m , and is in fact the pin p , as seen in Figs. 3 and 4 of the drawings. In this arrangement the spindle attached to crown M^2 within the stem M has a movement radially to a limited extent, and when said crown is pressed inward the said spindle comes in contact with the lever i . The fork of said lever i clasping the pin m^3 of lever i' the latter is moved, and its fork clasping the pin p of the yoke-arm a the wheel d' is brought to engagement with the winding-wheel H. Drawing the spindle of the stem out releases the lever i , which now receives the influence of the spring k^2 . As the motion of said lever i is communicated to the lever i' , the pin p is pushed by the fork of said lever i' to bring the wheel d' to engagement with the wheel d , which latter communicates its motion when the crown M^2 is revolved to operate the setting mechanism.

Having thus described my invention, what

I claim as new, and desire to secure by Letters Patent, is—

1. In a watch, the interchangeable pivoted yoke having three arms or wings provided with a notch in one, to be engaged by a shifting-lever, and all three of said arms or wings arranged for gear-wheels, as and for the purpose set forth. 40

2. The combination, with the triple yoke pivoted opposite the first quarter-point of the dial and the gear-wheels d d' , of the winding-wheel H, a gear-wheel about the pivot of said yoke, the setting-pinion x , the minute-wheel 50 A, a rotary spindle within the watch-stem, the cap L, and the wheel and pinion connected therewith, as and for the purpose specified. 45

3. The combination, with the yoke, a gear-wheel arranged about said point as an axis, the winding-pinion x' , the pin p in said yoke projecting through a suitable slot in the movement-frame, the levers i i' , the spring k , and the spindle in the stem and the wheel d' in the arm b , of the winding-wheel H, the wheel 60 b , the wheel A, the cap L, and the pinion and wheel f h , whereby when the yoke is shifted by the withdrawal or the pushing of the said stem-spindle the wheel d' will be brought in proper relation with the setting or winding 65 wheel to set or wind the watch from the stem, as set forth. 55

In testimony whereof I affix my signature in presence of two witnesses.

BERNARD HEIDBRINK.
